UNITED STATES PATENT OFFICE.

LAURA JANES GOTTL, OF LA GRANGE, OHIO.

IMPROVEMENT IN CAR-COUPING PINS.

Specification forming part of Letters Patent No. 149,743, dated April 14, 1874; application filed November 20, 1873.

To all whom it may concern:

Be it known that I, LAURA JANES GOTTL, of La Grange, in the county of Lorain and State of Ohio, have invented a new and useful Machine, called "Shackle-Pin Fastener," to prevent the coupling-pin in railway-cars from working out; and I do declare the accompanying is a full and exact description.

The object of my invention is to provide an attachment for the railroad-car shackle-pin, which will prevent the pin from working out of the pin-hole in the draw-bar of the car, and causing the cars to become detached while in motion. It consists of an attachment to the ordinary railroad-car coupling-pin.

The pin is manufactured for its accommodation thus: A hole, large enough to admit an iron rod one-fourth ($\frac{1}{4}$) of an inch in diameter, is drilled through the pin A from end to end, passing through the center. In the lower end of the pin A is drilled a hole about three-fourths ($\frac{3}{4}$) of an inch in diameter, and one inch deep. Through the hole in the pin A is passed the small iron rod B, one-fourth ($\frac{1}{4}$) of an inch in diameter, which extends below the lower end of the pin about one-half ($\frac{1}{2}$) of an inch, and the other end extends above the upper end of the pin, when straight, far enough to bend over, forming a loop, C, for the hand. The lower end of the loop forms a shoulder, which prevents the rod B from slipping down farther than necessary. On the lower end of the rod B is a flat forged head, and formed over this, in the molds, is a rubber attachment of one piece of rubber, consisting of a rubber cylinder, D, about three-fourths ($\frac{3}{4}$) of an

inch in length, and one and one-fourth ($1\frac{1}{4}$) of an inch in diameter, the rod running through the center of said attachment D from end to end. On the lower end of this is formed a circular rubber plate or flange one-eighth ($\frac{1}{8}$) of an inch or more in thickness and two (2) inches in diameter. This rubber attachment is drawn into the cavity in the lower end of the pin A by pulling up on the small rod B, and, while thus adjusted, the lower end of the pin A is unobstructed, and can be readily inserted in the hole in the draw-bar of the car. When in, the lower end extending through the draw-bar, the rubber attachment is forced out of the cavity by pressing on the small rod, and the plate or flange resumes its extended or natural position. It being at right angles with the pin A, and larger than the pin-hole in the draw-bar, the pin is prevented from working out by reason of the motion of the cars.

I am aware that I am not the first to invent a device for preventing the accidental displacement of the coupling-pin, for such a device is embraced in patent to S. A. Otis, October 7, 1873, and such I do not claim, broadly; but

What I do claim as my invention, and desire to secure by Letters Patent, is—

The coupling-pin A, rod B, and rubber block D, combined as and for the purpose set forth.

LAURA JANES GOTTL.
